J. LEDWINKA.
SHEET METAL CAN.
APPLICATION FILED MAR. 24, 1920.

Patented Mar. 1, 1921.

UNITED STATES PATENT OFFICE.

JOSEPH LEDWINKA, OF PHILADELPHIA, PENNSYLVANIA.

SHEET-METAL CAN.

1,370,134.

Specification of Letters Patent.

Patented Mar. 1, 1921.

Application filed March 24, 1920. Serial No. 368,266.

To all whom it may concern:

Be it known that I, JOSEPH LEDWINKA, a citizen of the United States, residing at Philadelphia, in the county of Philadelphia, 5 State of Pennsylvania, have made a certain new and useful Invention in Sheet-Metal Cans, of which the following is a specification.

This invention relates to sheet metal cans 10 or containers especially adapted for use in handling and shipping various substances which are required to be shipped in sealed receptacles.

The object of the invention is to provide 15 a sheet metal can or receptacle which is simple in structure, economical to manufacture, and strong and durable in use.

A further object of the invention is to provide a closure or cover for sheet metal 20 cans or receptacles, and means for detachably securing the same in place to effect a tight joint.

A further object of the invention is to 25 avoid the difficulties heretofore encountered in the construction of sheet metal cans and closures therefor and securing devices for securing the closure or cover to the can.

A further object of the invention is to 30 provide a sheet metal can structure to which a label may be applied, and wherein the label is protected against danger of defacement or injury in handling or transporting the cans.

Other objects of the invention will appear 35 more fully hereinafter.

The invention consists substantially in 40 the construction, combination, location, and relative arrangement of parts, all as will be more fully hereinafter set forth, as shown in the accompanying drawing, and finally pointed out in the appended claims.

In the drawing,—

Figure 1 is a view partly in elevation, and partly in central longitudinal section, 45 of a sheet metal can structure embodying the principles of my invention.

Fig. 2 is a broken detail view in perspective showing a portion of the open end of the can and the application thereto of 50 a cover or closure in accordance with the principles of my invention.

Fig. 3 is a broken detail view in section on the line 3, 3, Fig. 1, looking in the direction of the arrows.

It has heretofore been proposed to form 55 sheet metal cans or receptacles with a clo-

sure or top therefor, and to secure the closure or cover by means of tongues formed integrally with the body of the can at its open end which are threaded through slits 60 formed in the edge or rim of the cover or top. In such a structure the difficulty is encountered in assembling the cover in place of securing accurate alinement of the slits or openings through the rim of the cover 65 through which the securing tongues or prongs are threaded, thereby consuming time in assembling and materially adding to the cost of construction.

It is among the special purposes of my 70 present invention to provide a structure of can and top or cover therefor in which the cover may be quickly and easily assembled in place without necessitating care or attention in securing registration or positioning of the top or cover, and wherein the top or cover may be quickly and easily applied and secured in position or detached and removed therefrom when required.

The body 4 of the can embodying my 80 invention is formed in any suitable, convenient or well known way, into a cylindrical or other conveniently shaped structure, and secured at the edges thereof in any convenient or well known manner to produce a 85 tight joint. To one end of the body 4 a closure or bottom member 5 is applied and secured permanently in any well known manner at its edges to one end of the body 4 to form a leak-proof joint. At its other 90 end the sheet metal forming the body 4 is flanged or bent inwardly as at 6 and then outwardly upon itself as at 7 to form a fold constituting an interiorly extending shoulder or flange. The outwardly bent portion 95 7 of the fold is then turned upwardly, or in prolongation with the body 4, and at its extremity is formed into a series of tongues 8. Each tongue terminates in an outwardly or laterally extending flange or projection 100 indicated at 20. Adapted to be applied to the open end of the body is a top or cover 9. At its peripheral edge the top or cover 9 is pressed outwardly away from the plane of the body of the top or cover as indicated at 10 to form an interior channel, the open side of which presents downwardly toward the flange 6, 7, of the body, and adapted to coöperate therewith to form a joint. At its extreme edge the metal of 105 the top or cover 9 is bent upwardly or away from the plane of the outer surface of the

top or cover indicated at 11, and thence is folded backwardly upon itself as at 12 to form an upstanding integral rib at the boundary edge of the top or cover.

5 In applying the top or cover to the body 4 said cover is merely placed in position with its interiorly presenting channel rim portion 10 positioned and supported upon the interiorly extending flange 6, 7, of the 10 body, and with the outwardly extending rib portion 11, 12, fitting against the inner wall of the extreme edge of the body portion 4. The tongues 8 are then bent or deflected over upon the rib 11, 12, thereby 15 efficiently securing the cover in place. When the tongues 8 are thus bent over and upon the rib 11, 12, the terminal flange or projection 20 of the tongues lies slightly above and parallel with the plane of the outer 20 surface of the channel 10 of the cover so that by engaging a suitable tool beneath such flanges or projections 20, they may be pried open so as to release their engagement over the rib 11, 12, thereby permitting 25 the cover to be quickly and easily detached for removal from the can. If desired, and in order to insure a leak-proof joint of the top or cover with the body, a suitable compressible packing ring or gasket 13 is positioned 30 upon the supporting rib 6, 7, and received in the interiorly presenting channel formed at the peripheral edge of the top or cover 9. When the tongues 8 are clenched over the rib 11, 12, of the top or cover 35 the packing ring or gasket 13 is compressed, thereby forming an efficient locked and leak-proof joint.

If desired, and in order to afford strength and rigidity to the body of the can, suitable 40 grooves 14 may be pressed annularly into such body, thereby forming strengthening projections in such body.

In the handling and transportation of containers of the nature to which my invention 45 relates the labels customarily applied to such container or cans become injured or defaced through abrasion or friction, or otherwise. It is among the special purposes of my present invention to provide means 50 whereby this difficulty is avoided, and in accomplishing the desired purposes I propose to locate the label indicated at 15 intermediate adjacent body ribs 14 whereby the label will be protected by reason of being 55 located within the boundary of the projections formed by the adjacent grooves 14. If desired, however, the body of the can may be formed with a depressed annular portion 16 in which the label is seated so 60 as to lie within the boundary of the exterior surface of the receptacle or container, thereby efficiently protecting the same against possible defacement or injury while being handled or transported.

65 From the foregoing description it will

be seen that I provide an exceedingly simple, inexpensive, strong, durable, rugged and efficient container in which various materials may be packed and transported.

Having now set forth the objects and nature 70 of my invention and a construction embodying the principles thereof, what I claim as new and useful and of my own invention and desire to secure by Letters Patent is,—

1. In a sheet metal can structure, a body 75 portion having an inwardly extending integral flange adjacent to one end thereof, the metal of such body at said end beyond said flange being formed at the extremity thereof into tongues, in combination with 80 a top or cover positioned wholly within the end of the body and supported upon said flange and having its peripheral edge formed with an upturned flange portion, said top or cover adapted to be held in place 85 by bending said tongues inwardly over the upturned peripheral edge flange portion of said top or cover.

2. A sheet metal can structure having a body portion formed adjacent one end with 90 an inwardly extending bent or folded portion of the metal thereof to form an interior shoulder or flange, the extreme edge or end of said body portion being formed with tongues, in combination with a top or cover 95 adapted to be positioned wholly within the open end of the body and supported upon said flange, the extreme peripheral edge of said top or cover formed with an upstanding flange, said cover adapted to be retained 100 in position by clenching said tongues inwardly over said folded upstanding flange or edge.

3. In a sheet metal can structure, a body portion formed with an inwardly extending 105 fold adjacent one end thereof to form a shoulder or interior flange, the extremity of the body portion being formed into tongues, in combination with a top or cover having an outwardly pressed channel at its peripheral edge adapted to be positioned above 110 and supported upon said flange, the extremity of the peripheral edge of said top or cover being bent outwardly from the plane thereof and backwardly folded upon 115 itself to form an upstanding rib over which said tongues are clenched to secure the top or cover in place.

4. In a sheet metal can structure, a body portion formed with an inwardly extending 120 fold adjacent one end thereof to form a shoulder or interior flange, the extremity of the body portion being formed into tongues, in combination with a top or cover having an outwardly pressed channel at its peripheral edge adapted to be positioned above 125 and supported upon said flange, the extremity of the peripheral edge of said top or cover being bent outwardly from the plane thereof and backwardly folded upon 130

itself to form an upstanding rib over which said tongues are clenched to secure the top or cover in place, and a compressible packing or gasket interposed between said flange 5 and received in the open side of said channel.

5. In a sheet metal can structure, a body portion having an inwardly extending integral flange adjacent the end thereof, the metal of such body being at the extremity of such end formed into tongues, said tongues terminating in laterally extending flanges or projections, in combination with a top or cover positioned within the end of 10 the body and supported upon said inwardly extending integral flange, and held in place by bending said tongues over the peripheral edge of said top or cover, the lateral flanges or projections at the extremities of said 15 tongues affording means to release said 20

tongues from their engagement over the peripheral edge of the top or cover to permit detachment and removal of the latter.

6. In a sheet metal can structure, a body having an inwardly extending integral flange 25 adjacent the end thereof, the extremity of said end being formed into tongues, said tongues terminating in laterally extending flanges, in combination with a top or cover supported at its peripheral edge upon said integral 30 flange, and adapted to be detachably secured in place by bending said tongues over the peripheral edge thereof, the flanges at the extremities of said tongues when bent over, lying above the plane of the outer surface 35 of the top or cover.

In testimony whereof I have hereunto set my hand on this 15th day of March A. D., 1920.

JOSEPH LEDWINKA.
